UNITED STATES PATENT OFFICE

1,981,662

CHECK PROTECTING DEVICE

Leopold Pollock, New York, N. Y.

Application April 21, 1932, Serial No. 606,553

9 Claims. (Cl. 101—24)

This invention relates to check protecting devices. It is particularly directed to a fountain pen having a cap provided with devices for mutilating portions of written papers to prevent forging or alteration thereof.

An object of the invention is to provide a protective device of the character described which may be compactly incorporated into a fountain pen cap, the construction including means for protecting and housing the pen point of the fountain pen.

A further object of this invention is to provide in a protective device having a pair of spring arms adapted to be pressed toward each other, highly improved means within said arms for piercing or perforating a sheet inserted between said arms, the construction being easy to assemble and positive and smooth in operation.

A still further object of the invention is to provide a device of the character described which shall be neat and compact in construction, comparatively inexpensive to manufacture, easy to manipulate for positioning the perforated members at the portions of the paper to be perforated and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompany drawing, in which is shown one of the various possible illustrative embodiments of this invention,

Fig. 1 is a side elevational view of a fountain pen embodying the invention with parts broken away to show the interior construction;

Fig. 2 is an enlarged cross-sectional view of my improved fountain pen cap;

Fig. 3 is a cross-sectional view taken on line 3—3 of Fig. 2;

Fig. 4 is a perspective view of the cap showing the same in position for perforating a check;

Fig. 5 is a cross-sectional view taken on line 5—5 of Fig. 4;

Fig. 6 is a cross-sectional view taken on line 6—6 of Fig. 5; and

Fig. 7 is a perspective view of one of the rollers and its frame.

Referring now in detail to the drawing, 10 designates a fountain pen embodying the invention comprising in general a barrel 11 to one

end of which there is attached the usual pen point 12, and a cap 13 screwed to the barrel in the usual manner, as hereinafter described. The barrel 11 may be of ordinary construction and comprises the screw threaded portion 14 60 and a tapering or frusto-conical shaped portion 15 adjacent one end thereof. The cap 13 comprises a tubular member 13a having an open end 15a. Adjacent said open end, the member 13a is provided with an inwardly extending annular member 18 having internal screw threads adapted to cooperate with the threaded portion 14 for screwing the barrel 11 to said cap.

The tubular member 13a may be provided with a pair of diametrically disposed longitudinal slots 19 and 20, terminating short of the flange portion 18 of said cap, as clearly shown in Fig. 2 of said drawing, to form two somewhat resilient arms 22 and 23 which may be pressed toward one another.

Adjacent the outer end of each arm there is fixed a frame 24 comprising a pair of substantially semi-circular parallel portions 25 and 26, the peripheral edges of which contact the inner surface of said arm, and a flat portion 27 interconnecting said portions 25 and 26, and disposed flush with the edges formed at the slots 19 and 20. Each flat wall portion 27 is provided with a preferably oblong shaped opening 28 for the purpose hereinafter appearing.

The frames 24 may be attached to said arms 22 and 23 by means of projections 29 extending from the wall portions 25 and 26 and passing through openings 29a formed in the cap for this purpose. The opposite walls 25 and 26 of each frame, are formed with a pair of aligned openings 30 and fixed within one pair of aligned openings is a shaft 31 on which is rotatably mounted a roller 31a having a plurality of parallel, spaced annular peripherally serrated portions forming sets of points or teeth 32, adapted to partially project through the opening 28 in one of the frames. Fixed in the other pair of aligned openings 30 is a shaft 33 on which there is rotatably mounted a roller 33a having parallel, spaced, thin circular plates or portions 34 preferably disposed between the serrated portions and projecting through the opening 28 in the other frame 24. Thus, should a paper be inserted within the slots 19, 20 and the two opposite sides or arms of the cap pressed together and the cap then moved along the paper, the teeth 32 will pierce or perforate the paper for protecting any written portions of said paper against forging or alterations, the circular por-

tions 34 serving to press the paper against said teeth.

For closing the ends of the semi-circular arms 22 and 23, said arms are provided adjacent the outer ends thereof with aligned semi-circular grooves 50. Received over each of said ends is an end member 16 having a semi-circular flat wall portion 16a from which there extends a flat inner portion 17 substantially flush with the wall 27 of one of the frames 24. Each member 16 further comprises a cylindrical portion 17a crimped as at 17b into one of the grooves 50 for retaining the said member in position. Extending inwardly from the ends of the cylindrical portion 17a of each member 16 are inwardly bent portions 21 likewise substantially flush with the wall 27 of one of the roller frames 24. It will thus be seen that the perforating device may be readily mounted within the arms 22 and 23. The shafts 31 and 33 are first fixed within the frames 24 with the rollers rotatably mounted on said shafts. The frames are then inserted within the arms through the outer ends thereof and the lugs 29 inserted within the openings 29a and upset slightly to firmly rivet said frames to said arms. The end members 16 are then applied for covering the outer ends of said arms. Obviously the roller assembly may be applied to any perforating or protecting device having a pair of spring arms which may be pressed toward each other, the invention not being limited only to a tubular member or a cap for a fountain pen, pencil or the like instrument.

Means is provided for adjustably positioning the perforating rollers 31a, 33a from the edge of the check or paper to be perforated, whereby, as shown in Fig. 4 of the drawing, a check for example, may be inserted within the slots 19, 20 to any suitable distance from the edge of said check and the position of the rollers with respect to said edge maintained as the cap is moved from left to right for perforating a line of writing on said check. To this end there is slidably mounted within said cap 13, a tubular member 35 having an end wall 36 provided with diametrically oppositely disposed portions 37 extending through the slots 19 and 20, said portions 37 being provided with wings or ears 38 contacting the outer surface of the cap on opposite sides of said slots. Said tubular member 35 may be further provided with a shoulder portion 35a adjacent the end wall portion thereof, adapted to guide said tubular member 35 through the open end of the cap 13 and prevent wobbling of said member. Said members 37 or shoulder 35a limit outward movement of said member 35. The tubular member 35, as shown on the drawing, is open at the lower end thereof and adapted to receive the pen point 12 and the outer end of the barrel 11. Thus upon inserting the pen point portion of the barrel 11 within said tubular member 35, the outer edge 39 of said tubular member will contact the conical portion of the barrel, thus forming a chamber for housing the pen point and sealing said chamber to prevent leakage or evaporation of the ink. Said tubular member 35 may be provided, however, with small openings 40 adjacent the end wall 36 to permit air to enter said tubular member, air obviously passing through the slots 19 or 20 for this purpose.

When the barrel 11 is screwed to the cap 13, the edges 39 will contact the conical portion 15 of said barrel and prevent the end or

tip 42 of the pen point from striking the inner surface of said end wall 36, thus protecting the tip of said pen point. When using the cap for perforating a piece of paper, the barrel 11 is first unscrewed to permit the tubular member 35 to be moved to any desired position. Preferably there is sufficient friction between the members 37 and the edges of the cap at said slots 19 and 20 for retaining the tubular member 35 in any adjusted position to which same may be moved. Although the cap is shown attached to a barrel of a fountain pen, it will be understood that said cap may be also attached to a pencil having a tapered end, or any other suitable instrument or may be used alone. A spring clip 45 may be attached to the outer side of the cap to permit the same to be attached to a pocket.

It will be understood that after the tubular member 35 has been moved to any desired adjusted position and a sheet inserted between the two arms 22 and 23, pressure on said arms toward each other will cause the edges of said arms to press against the portions 37 extending through the slots 19 and 20 for maintaining the tubular member in said adjusted position while the sheet is being perforated.

It will thus be seen that there is provided a device in which the several objects of this invention are achieved, and which is well adapted to meet the conditions of practical use.

As various possible embodiments might be made of the above invention, and as various changes might be made in the embodiment above set forth, it is to be understood that all matter herein set forth, or shown in the accompanying drawing, is to be interpreted as illustrative and not in a limiting sense.

Having thus described my invention, I claim as new and desire to secure by Letters Patent:

1. A fountain pen comprising, in combination, a barrel having a pen point at one end, a tubular member open at one end thereof screwed to said barrel, the other end of said member being slit for receiving a sheet of paper, means mounted within said member for mutilating a portion of said sheet, and adjustable stop means adapted to contact an edge of said sheet, said means comprising a tubular member slidably mounted within said first member and having an end wall at one end thereof and being open at the opposite end thereof, and receiving said pen point in said open end thereof.

2. A fountain pen comprising, in combination, a barrel having a pen point at one end thereof, a cap screwed to said barrel, said cap being slit at the outer end thereof to form arms and having means in said arms for perforating a sheet of paper inserted within said slit, and a tubular member within said cap having a portion for housing said pen point.

3. A fountain pen comprising, in combination, a barrel having a pen point at one end thereof, a cap screwed to said barrel, said cap being slit at the outer end thereof and having means for perforating a sheet of paper inserted within said slit, and a tubular member within said cap having an end wall adapted to contact the edge of a sheet inserted in said slit, and a portion for housing said pen point.

4. A fountain pen comprising, in combination, a barrel having a pen point at one end, a slit tubular member screwed to said barrel and forming arms, a pair of rollers mounted in said

- arms for perforating a sheet of paper inserted in the slit of said tubular member, and a second tubular member slidably mounted within said cap, said last mentioned tubular member 5 being open at the outer end thereof and receiving said pen point, and means for limiting outward movement of said tubular member.
5. In a fountain pen, a barrel having a pen point, a tubular member screwed to said barrel 10 and being provided with a pair of diametrically disposed longitudinal slots forming arms, means within said arms for perforating a sheet inserted into said slots and a tubular member slidably mounted within said first tubular member receiving said pen point and having a portion extending through one of said longitudinal slots, and stop means for preventing removal of said second tubular member from said first tubular member.
20. 6. In combination, an instrument having an end portion, a tubular cap open at one end and closed at the opposite end, screwed to said instrument with said end portion of said instrument extending within said cap, and a tubular member slidably mounted within said cap and adapted to move through the open end of said cap, said tubular member being open at one end thereof, said end portion extending within said tubular member through the open end thereof.
25. 7. In combination, an instrument having an end portion, a tubular cap open at one end and closed at the other end, screwed to said instrument with the end portion of said instrument extending within the open end of said cap, and a tubular member slidably mounted within said cap, said tubular member being open at one end thereof and closed at the other end thereof, and adapted to move through the open end of said cap, said end portion extending within said
- tubular member through the open end thereof, and stop means for preventing removal of said tubular member from said cap.
8. A tubular member provided with a pair of longitudinal, diametrically disposed slots forming arms of semi-circular cross-section adapted to be pressed toward one another, a frame mounted within each arm, each frame comprising a pair of parallel, semi-circular, spaced walls contacting the inner surfaces of one arm and interconnected by a flat wall substantially in the plane of said slots, said flat wall being formed with a central opening, said semi-circular walls being provided with lugs, and said arms being provided with openings for receiving said lugs, and a roller mounted on said spaced semi-circular walls of each frame and having a portion projecting through said central opening.
80. 9. A tubular member provided with a pair of longitudinal, diametrically disposed slots forming arms of semi-circular cross-section adapted to be pressed toward one another, a frame mounted within each arm, each frame comprising a pair of parallel, semi-circular, spaced walls 100 contacting the inner surfaces of one arm and interconnected by a flat wall substantially in the plane of said slots, said flat wall being formed with a central opening, said semi-circular walls being provided with lugs and said arms being 105 provided with openings for receiving said lugs, and a roller mounted on said spaced semi-circular walls of each frame and having portions projecting through said central opening, one of said rollers being provided with a plurality of 110 spaced, parallel, peripherally serrated portions, and said other roller being provided with a plurality of spaced parallel circular portions disposed between said serrated portions.
